Primary Examiner—Marcus A. Jackson**Attorney, Agent, or Firm**—Burd, Bartz & Gutenkauf**[57]****CLAIM**

The ornamental design for a adjustable sign holder, as shown and described.

DESCRIPTION

FIG. 1 is a perspective view showing the adjustable sign holder of my new design;

FIG. 2 is a foreshortened side elevational view thereof, the opposite side being a mirror image thereof, with the portion broken away to indicate indeterminate length;

FIG. 3 is a foreshortened top plan view thereof;

FIG. 4 is a foreshortened bottom plan view thereof;

FIG. 5 is an enlarged end elevational view thereof;

FIG. 6 is an enlarged sectional view taken along the line 6—6 of FIG. 2; and,

FIG. 7 is an enlarged sectional view taken along the line 7—7 of FIG. 2.
